UNITED STATES PATENT OFFICE.

ALFRED SAFKA AND JOSEPH C. SAFKA, OF PHILADELPHIA, PENNSYLVANIA.

LAPPING-HEAD.

1,284,786.

Specification of Letters Patent.

Patented Nov. 12, 1918.

Application filed July 20, 1918. Serial No. 245,895.

To all whom it may concern:

Be it known that we, ALFRED SAFKA and JOSEPH CHARLES SAFKA, citizens of the United States, residing at 5781 Cedar Ave. 5 and 2929 Poplar St., respectively, Philadelphia, in the county of Philadelphia and State of Pennsylvania, have invented new and useful Improvements in Lapping-Heads, of which the following is a specification.

10 This invention relates to certain new and useful improvements in lapping heads, such as are usually employed for finishing the bores of guns, cylinders and the like.

The main object of our invention is to 15 provide a positive tool of the type referred to which can be used at very high speed, whereby a great saving of time is effected.

16 A further object of our invention is to provide a simple, efficient and durable lapping tool which comprehends certain novel features whereby better results are obtained, and which by the nature of its construction is rendered portable, and further, it can be 20 employed in any desired position.

25 With these and other objects in view, this invention consists in the details of construction and combination of parts hereinafter set forth and then specifically pointed out by the appended claims. In order that those skilled in the art to which this invention 30 appertains may understand how to make and use the same, the construction and operation will now be described in detail, reference being had to the accompanying drawing, 35 forming a part of this specification, and in which—

Figure 1 is a combined horizontal longitudinal section and elevation of the lapping head.

40 Fig. 2 is an end elevation of the lapping head with the end pieces removed.

Fig. 3 is a plan view of the lapping head as seen when assembled.

Fig. 4 is an end elevation of Fig. 3, as 45 seen when assembled.

Fig. 5 is a section of the end pieces or disks showing the construction of the spring operating and releasing mechanism.

Fig. 6 is a sectional elevation showing 50 the construction of the guides and spring collapsing mechanism, and

Fig. 7 is a perspective view of the clamp for holding the sheet or sheets of abrasive material taut about laps.

55 Referring to the drawings the letter A represents a hollow shaft upon which the

lapping head is fastened, and which is the medium by which the power to operate the lapping head is transmitted. B and B' are the lap plates upon which the sheets containing the abrasive material are placed, and to which these sheets are clamped by means of the clamping bars C which are secured to the laps B and B' by pins C' and clamped tight on the sheets by wing nuts C² threaded 60 on studs C¹. The lap plates B and B' are prevented from moving laterally and transversely to any great extent by guide pins B² which are screwed into and fastened rigidly to the lap plates. The lap plates 65 are further prevented from moving laterally and transversely by pins B³, which are also screwed into and fastened rigidly to the lap plates, and which also serve as guides. The principal use, however, of the pin B³, 70 75 is to operate in conjunction with the springs B⁴, which are held in place by nuts B⁵. The parts B², B³, B⁴ and B⁵ operate in spiders D and D' which are keyed by a key D² and securely bolted to the hollow shaft A. The 80 spiders D and D' thus comprise two parts having three vertical arms each. E and E' are disks which bear against the ends of the lap plates B and B' thus forcing the lap plates B and B' with the sheets containing 85 abrasive material against the surface of the work to be finished or lapped. These disks E and E' are controlled by the springs E² interposed between the collars F and shoulders formed in the disks. The collars F 90 are secured to the hollow shaft A by pins F', The disks E and E' are thus free to move longitudinally over the hollow shaft A and collars F. The shaft G is a releasing shaft operating within the hollow shaft A. 95

The operation of the lapping head is as follows: Referring to Fig. 1 the disk E is drawn longitudinally along the hollow shaft A and sliding over the collar F, which operation compresses the spring E² and 100 draws along with it the solid or releasing shaft G, which operates within the hollow shaft A, and by means of pin H the pin J is drawn through the inclined slots in disk E', thereby imparting a slight rotating motion to the disk E' and in this manner pushing it away from the ends of the lap plates B and B', thus both disks E and E' are free from the lap plates. This allows the springs B⁴ to expand against the nuts B⁵ 105 which are secured to the pins B³ and in this manner drawing or collapsing the lap plates 110.

B and B' at right angles to and toward the hollow shaft A.

The lapping head is then inserted into the work, and disk E released which also releases disk E', by means of the shaft G, pins H and J, from the ends of the lap plates B and B'. This operation also causes the springs B⁴ to extend along the pins B³ interposed between the nuts B⁵ and the 10 shouldered-in arms of the spiders D and D'. This mechanism is intended to partly equalize the centrifugal force when the entire lapping head is rotating and partly as a guide and steadier—operating within the 15 arms of spiders D and D'—for the laps B and B', but mainly as a collapsing mechanism to cause lap plates B and B' to collapse toward hollow shaft A, when inserting the entire lapping head into or removing it 20 from the work being finished or lapped. The guide pins B² are the main guiding and steady pins, also operating within the arms of spiders D and D'. The hollow shaft A is then caused to rotate and this 25 in turn rotates the entire lapping head as a unit thus performing the work for which the machine is intended.

Releasing the machine from the work is accomplished by the same operation as 30 when inserting the machine into the work.

While we have fully described our practical embodiment of our invention we wish it to be clearly understood, that we do not limit ourselves to the exact construction 35 shown, as slight modifications can be made without departing from the spirit and scope of our invention.

We claim:

1. A lapping head comprising a hollow 40 shaft, spring-controlled lapping members mounted on said hollow shaft, spring-influenced disk members adapted to coöperate with said lapping members and force them outwardly by centrifugal force, and means 45 for separating the said disks to contract the lapping members.

2. A lapping head comprising a hollow 50 shaft, arcuate lapping members mounted on said shaft, contractile springs acting upon said lapping members, spring-influenced disk members adapted for coöperation with

the ends of said lapping members and normally tending to expand the same, and means for moving one of said disks longitudinally and the other spirally of said 55 hollow shaft to contract the lapping members.

3. A lapping head comprising a hollow shaft, arcuate lapping members mounted on said hollow shaft, contractile springs operating upon said lapping members, spring-influenced disk members adapted for coöperation with the ends of said lapping members and tending to expand the same, means for moving one of said disks longitudinally 60 and the other spirally of said hollow shaft to contract the lapping members, and means for holding the abrading material on the lapping members.

4. A lapping head comprising a hollow 70 shaft, arcuate spring actuated lapping members mounted on said hollow shaft, spring-influenced disk members coöoperating with the ends of said lapping members to expand the same, an inner shaft having operative connection with the disk members whereby one of said disk members may be moved longitudinally and the other spirally of said 75 hollow shaft to contract the lapping members, and clamping bars for holding the 80 sheets of abrading material on the lapping members.

5. A lapping head comprising a hollow shaft, opposed spider members mounted on 85 said shaft, lapping members having operative connection with the said spider members, contractile springs operating upon said lapping members, spring-influenced disk members coöoperating with the ends of 90 the lapping members to normally expand the same, an inner shaft having operative connection with the disk members whereby one of said disk members may be moved longitudinally and the other spirally of said 95 hollow shaft, and clamping bars for holding the sheets of abrading material on the lapping members.

In testimony whereof we affix our signatures.

ALFRED SAFKA.
JOSEPH C. SAFKA.
